ELECTRIC FUSE

Franklin S. Klein, Malverne, N. Y.

Application May 6, 1938, Serial No. 206,473

9 Claims. (Cl. 200—121)

This invention relates to electric fuses which form a fusible link in an electric circuit.

The object of the invention is to provide an improvement in enclosed fuses whereby the fusible link cannot be tampered with or renewed, or reinforced, or any form of metal used to reestablish the circuit through the fuse case; and because these fuses are useless after one rupture of the fuse link. It is another object to provide an inexpensive but reliable fuse including a direct and ample vent for the combustion chamber together with an efficient device for indicating a ruptured fuse link and ventilating the fuse case at all times.

In my application #273,883, filed May 15, 1939, as a substitute for my earlier application #157,288, filed August 6, 1937, for "Electric fuse," there are certain "time lag" and "arc blocking" features described which are also indicated in the present application, but the invention herein disclosed is for further objects which include tamperproofing and economy, whereas said application No. 273,883 includes no such inexpensive structure or reliable tamperproofing as herein disclosed, but provides an improvement to fuse links of the open or enclosed type which may be replaced or tampered with.

The object of this invention is attained by having the end part of an enclosed fuse case, which is usually hollow, arranged to form a substantially solid and unmanageable or refractory mass of nonconducting material including a portion of the potentially fusible part of the fuse link in said mass, to prevent tampering with the valve of the fuse link. The use of preformed blocks of suitable material plugged into the ends of the combustion chamber of a fuse case and cemented in position is contemplated, but so far as may be practicable and because of the economy, a cement is preferred, which will adhere with both the fusible link and the fuse case thereby forming the cement and a portion of the fusible section of the link and part of the fuse case into a permanent or non-tamperable mass which also forms an economical means for fixing the external electrical contact members in position.

For example, a mixture of plaster of Paris and water poured into an end part of the combustion chamber of an enclosed fuse, to form a sufficient mass for the object in view, would serve the purpose quite well, but there are other materials much more difficult to tamper with, for instance a cement containing a quantity of porcelain particles would be heat conducting and extremely difficult to drill or chip or remove and

when the aforementioned plugs or cement consist of heat conducting, flameproof material, there are desirable "time lag" and "arc blocking" features provided.

5 When an enclosed fuse is provided with the aforesaid cement device, and the fuse link electrically disrupted, the arc accompanying the disruption will extend up to or into the cement a very short distance, leaving a charred end of the link which could not be reconnected for any practical purpose.

In the accompanying drawing, those well known types of fuses which have been illustrated, embody my invention, and Fig. 1 is a view of a 15 cartridge fuse having terminals of the ferrule type and the case partly broken away to show the plug of tamperproofing cement at 11.

Fig. 2 is a sectional view of an inexpensive 20 cartridge fuse which as a whole, may be used as the renewable element in a fuse case for renewable fuse links, showing cement at 11 plugging each end of the casing also a vent 22.

Fig. 3 is a sectional view of a cartridge fuse 25 including features of Fig. 2, but having a stronger casing with end caps, substantial knife blade terminals, a ruptured fuse link, and a device 25 indicating a ruptured fuse.

Fig. 4 is an end view of one of the caps for 30 finishing the ends of the cartridge fuse at Fig. 3, and includes a perforated fragile indicating label 25 over the outlet of the vent tube.

Fig. 5 shows an embodiment of the invention in a screw plug fuse.

In further detail the numerals 6 each indicates 35 a fuse casing composed of tough dielectric, that is, nonconducting material, having a combustion chamber 7, a fuse link 8 in said chamber, and said link connected to external electrical contact terminals 9 and 10, also cement 11 which is 40 poured into the fuse case after the fuse link has been set in position. This arrangement is shown at Fig. 1, also at Fig. 5 where a typical screw plug fuse is shown with a screw threaded contact shell at 9 and a bottom contact at 10 and the cement 11 is 45 has been poured into the combustion chamber 7 so as to present a surface 26 sloping toward the top of this fuse plug, thereby causing a rupture of the fuse link 8 where it can be clearly seen through the usual mica window 28 which is held 50 in place by the customary top capping 30.

In the fuse cases, the surfaces that come in contact with the cement will be made adaptable for anchoring or keying both together, for instance in cases comprising fibrous material the wall surface may be lacerated as at 13, as an

economical means of forming the cement and part of the fuse case into one unmanageable mass.

The fuse cases illustrated, show a considerable mass of cement, but it is to be understood that more or less of a really substantial body of cement may be used to accomplish the objects of the invention, in fact it is desirable to use the lesser amount and leave more space for the expansion of gas when the link disrupts.

The potentially fusible metal in fuse links is often completely volatilized, but a desirable amount of volatilization is not generally to be depended upon to extend up to or into the cement 11 and to char that end of the fuse link as previously described. It is therefore expedient to provide a relatively short and particularly fusible section 12 intermediate the ends of the fuse link 8; and arrange all to embed a part 17 of the fusible section 12 in the cement 11, which makes the charring of that end of the link more certain because a less fusible part 20 of the link is quite close or at least within arcing distance to the face 19 of the cement, then an arc can continue until part of the section 17 which is embedded in the mass 11, is charred as indicated by 21, in Fig. 3, where it is shown that a very small portion 18 of the less fusible part 20 has burned away in continuing the arc as desired.

Furthermore, by the arrangement just described, the mass of cement 11 cooperates with the less fusible parts of the fuse link as at 20, in conducting heat from that part of the fusible section which extends out of the mass, and causes the fusing thereof to be delayed, and, only a relatively short section of the whole link may be destroyed because the mass at 11 blocks an electric arc very close to the beginning of a rupture in the fuse link.

The exact length of the particularly fusible section at 12 is not a critical matter, but it must be definitely short with respect to the length of the whole fuse link; and to insure all of those functions inherent in my new fuse which includes important time lag and arc blocking features as well as tamperproofing; I prefer that section at 12 to be substantially as shown, that is, part of a unitary strip of fuse metal, of reduced cross-section and of a length less than one quarter of the distance between the contact terminals of a National Electrical Code standard fuse gap which varies according to the rating of the fuse. For example, the standard gap for a fuse rated at 600 amperes and 600 volts, is nine inches, but in such an instance the fusible section at 12 may be considerably less than one quarter of nine inches.

In a fuse arranged as thus far described, a necessary disruption of the fuse may occur freely and promptly, an electric arc will be blocked by the mass at 11, therefore the disruption will be brief and limited almost entirely to that end part of the short section 12 which extends from and clear of the mass at 11; the remainder of the short section 12 being embedded in refractory dielectric material, safe from an electric arc and tamperproof. Also when an overload of current is temporary—in other words not of harmful duration—the mass at 11 will naturally absorb heat from the short section at 12 and thereby effect a time lag—in other words, delay a disruption by said overload which may then subside without disrupting the fuse unnecessarily; the same delay is often asserted to be a function of a granulated filling in fuse cases, but the solid mass

shown at 11 is more effective, and by blocking the electric arc, it is safe to use unusually heavy metal in the less fusible portions as shown at 20 in the fuse link 8 to further expedite the conduction of heat from the fusible section 12 and increase the delay of a disruption.

In the cartridge fuse at Fig. 2, which may be used as the renewable element in renewable fuse cases, I have included the improvement as thus far described, and moreover the cement 11 is used to constitute the closure for each end of this tubular casing 6, and the same cement also provides the means for firmly fixing each end terminal 9 and 10 which are embedded in the cement 11 in the proper position, and in some instances the ends of the link itself shall extend beyond the ends of the fuse case 6 and constitute the terminals 9 and 10.

Fuse elements of the type shown at Fig. 2, are known to frequently burst because of the relatively flimsy casing having little or no venting, therefore I have provided an ample vent tube 22 which extends from the surface at the end of the fuse case, through the cement 11 in which it is anchored, and into the combustion chamber 7, and that end of the vent tube 22 which extends into the combustion chamber is provided with a multiple of perforations 23 forming a screen to baffle or prevent the passage therethrough of flame and small particles, but permit the exit of expanding gas; the end of the vent tube 22 which is in the chamber 7 is preferably closed by pinching at 29, this tube may be made from any suitable material.

At Fig. 3, the cartridge fuse shown has terminal members 9 and 10 of the knife blade type permanently fixed in the cement 11. This fuse includes the improvements previously described also the following; it is desirable that this fuse present a well finished appearance, therefore caps 14 and 15 composed of nonconducting material, are used on each end of this tubular casing 6 to cover the relatively crude appearance of the cement 11 and it will be seen that said caps form a convenient means for assembling the fuse. Each of the caps 14 and 15 are provided with a slot 16 for the terminal blades 9 and 10 and one of said caps is also provided with a hole 24 for the outlet end of the vent tube 22, and each cap has the inner surface lacerated 13 to key with the cement 11.

At Fig. 3, the outlet end of the vent tube 22 is covered by a label 25 which is more distinctly shown at Fig. 4, and which may be composed of paper cemented in position, said label is adapted to be broken by the pressure of a blast of expanding gas in its escape through the vent tube, thereby indicating a ruptured fuse.

The fuse at Fig. 3, as thus far described, would normally be without secondary ventilation, therefore the indicator label 25 is provided with perforations 23, which permits heated air to be gently exhaled directly from the most heated part of the enclosed fuse; and prevents charring of the casing, which is frequently caused by the fuse carrying the maximum current for long periods.

It is to be noted that an importantly improved result is provided for by the above described vent tube and label in combination, in that, the ample vent tube 22 has a perforated portion at 23 substantially in the middle of the combustion chamber, or in the vicinity of a disruption; and at the outlet end of the vent tube, the label 23 constitutes a closure which is adapted to hold

against the quickly expanding gas when the link is disrupted, until the pressure of gas is sufficient to displace said closure with an explosive blast through the tube, which results in the gas being so abruptly and copiously expelled that the extinguishment of the arc is materially promoted, and this result is partly due to the partial vacuum formed when gas is thus expelled.

In assembling the fuse at Fig. 3, the outlet end of the vent tube 22 is inserted in the hole 24 of the cap 15, then that cap, by means of the slit 16, is slipped over the terminal blade 10, and fitted on one end of the casing 6, then the cement 11 is poured into that end of the combustion chamber 7, the next space in the chamber 7 is then partly filled with a dry powder which may be plaster of Paris in relatively large granules 21, these granules serve to absorb the shock of a violent disruption, retard the progress of an arc, dissipate heat from the link 8, and also form a foundation for the necessary amount of cement plugging the other end of the casing 6, whereupon the cap 14 is slipped over the other terminal blade 9 and on that end of the casing with the lacerations 13 of the cap engaging with the cement 11 to anchor therewith as the cement hardens and also permanently fixes the terminals 9 and 10 in position, and finally the indicating label 25 is cemented in its place, although the indicator 25 may consist of a perforated plug frictionally held in the outlet end of the tube 22.

It must be obvious that a fuse constructed as that at Fig. 3, is less expensive to manufacture and more safe to handle than the usual fuse, because the usual metal end closures or ferrules have been eliminated and a minimum of metal is exposed, consequently reducing the possibility of bridging end ferrules with extra fuse metal and also reducing accidental electric shock when handling the fuse; and furthermore to tamper with this fuse, is very impractical and less economical than with more expensive enclosed fuses.

It is not deemed necessary to show all of the fuses to which this invention is applicable, and several modifications are contemplated to suit particular requirements or methods of manufacture, all of which are believed to be within the scope of the appended claims.

I claim:

1. In an enclosed electric fuse, the combination of a fuse link having a section equal to less than half its length so constructed as to be a particularly fusible section of the link, and, a dielectric casing having a substantial portion thereof arranged to form a refractory solid mass which includes at least half of said fusible section of the link to substantially prevent the fusing thereof, and prevent tampering with the value of the fuse link, the remainder of said fusible section of the link extending from said mass whereby, a disruption of the fuse link may be limited substantially to said remainder of the fusible section by said mass blocking an electric arc close to the disruption.

2. In an enclosed fuse, the combination of a casing having contact terminals, a strip of fusible metal having a relatively short section thereof, intermediate its end portions, reduced in cross-section and particularly fusible; and, a substantial body of material which is heat conducting, dielectric, and solid, arranged to form with said casing and a portion of said strip a refractory mass, an end portion of said short and particularly fusible section extending from said mass.

3. In an enclosed fuse, the combination of a casing having contact terminals, a strip of fusible metal having a relatively short section thereof, intermediate its end portions reduced in cross-section and particularly fusible, and, a body of heat conducting dielectric cement poured into an end of said casing and therewith forming a solid refractory mass which includes a cross-section of the casing and a substantial portion of said short and particularly fusible section of the strip, a portion of said short and particularly fusible section extending from said mass; whereby, heat may be conducted from said short section to retard fusing thereof, and a disruption in said strip may be limited substantially to said portion of the short section extending from said mass, and also a portion of said short section may be held in said mass safe from an electric arc and safe from tampering therewith.

4. In an enclosed fuse, the combination of a casing having contact terminals, a fusible strip having a section thereof which is more fusible and located intermediate less fusible portions of the strip, and, a body of material which is heat conducting, dielectric, solid, flameproof, and arranged to form with said casing and a portion of said more fusible section an unmanageable mass, one of said less fusible portions of the strip being within arcing distance of said mass with a relatively short portion of said more fusible section therebetween whereby, the less fusible portions of the strip and said mass cooperate to absorb heat from the more fusible section and retard the fusing thereof, and induce an arc to char and render unmanageable the end of the fusible section which is in said unmanageable mass, and the mass substantially limits a disruption of said fusible strip to that portion of the fusible section between the mass and the less fusible portion of strip by blocking an electric arc close to the beginning of a disruption.

5. In an enclosed cartridge fuse, the combination of a tubular casing having contact terminals and a combustion chamber, a strip of fusible metal having a relatively short section thereof reduced in cross-section and more fusible, and, a body of material which is heat conducting, dielectric, and refractory, and arranged in an end of said casing to form a refractory mass which includes a cross-section of the casing and an end part of said more fusible section of the strip, an end part of said more fusible section extending from said mass, a vent comprising a tube having a perforated portion, said tube being secured in position by said mass and extending through the mass with an end of the tube at the exterior of the fuse and said perforated portion within the combustion chamber of the fuse.

6. In an enclosed fuse having a casing provided with a combustion chamber, a fuse link therein, and contact terminals; a vent for said combustion chamber comprising, a hollow tube having a portion thereof provided with a multiple of perforations adapted to permit gas to pass therethrough and prevent the passage flame, said tube having an end at the external surface of said casing and a perforated portion within said combustion chamber.

7. In a cartridge fuse, a vent for the combustion chamber comprising a tube having a screened end in the combustion chamber and a perforated fragile cover on the outlet end.

8. A cartridge fuse comprising a tubular casing, an end of said casing closed by means of nonconducting material, a flame baffling vent

tube through said material and a perforated fragile cover over the outlet of said vent.

9. In a cartridge fuse having tubular casing, contact terminal, a combustion chamber, and a fuse link therein; a vent for said combustion chamber comprising, a hollow tube having a portion provided with perforations, and adapted to copiously vent gas and prevent the passage of flame, said tube having an outlet at the end of said casing and a perforated portion substantially

in the middle of said combustion chamber, in combination with a closure for said outlet of the tube, said closure being adapted to hold against quickly expanding gas until the pressure of gas is sufficient to displace said closure with an explosive blast whereby, when said link is disrupted gas is abruptly and copiously expelled and extinguishment of the arc promoted.

FRANKLIN S. KLEIN.
